United States Patent Office

Des. 231,565

Patented Apr. 30, 1974

231,565

TYPEWRITER

Toshihiko Sakow, Teaneck, N.J., assignor to Litton
Business Systems, Inc., New York, N.Y.

Filed Dec. 15, 1972, Ser. No. 315,439

Term of patent 14 years

Int. Cl. D18—01

U.S. Cl. D64—11 A

Fig. 1

Fig. 2

Fig.3

Fig.4

Fig.5

FIG. 1 is a front perspective view of a typewriter showing my new design;

FIG. 2 is a rear perspective view thereof;

FIG. 3 is a right side elevational view thereof;

FIG. 4 is a front elevational thereof; and

FIG. 5 is a rear elevational view thereof.

For clarity of illustration, portions of conventional mechanisms have been deleted from the figures in the drawing.

I claim:

The ornamental design for a typewriter, as shown.
